UNITED STATES PATENT OFFICE.

FRANCIS MARION CHAPPELL, OF NEWNAN, GEORGIA.

BALING-PRESS.

SPECIFICATION forming part of Letters Patent No. 702,626, dated June 17, 1902.

Application filed October 14, 1901. Serial No. 78,610. (No model.)

To all whom it may concern:

Be it known that I, FRANCIS MARION CHAPPELL, a citizen of the United States, residing at Newnan, in the county of Coweta and State of Georgia, have invented a new and useful Baling-Press, of which the following is a specification.

My invention is an improved baling-press adapted especially for baling hay, straw, and the like; and it consists in the peculiar construction and combination of devices herein-after fully set forth and claimed.

In the accompanying drawings, Figure 1 is a side elevation of a baling-press embodying my improvements. Fig. 2 is a top plan view of the same. Fig. 3 is a vertical transverse sectional view of the same. Fig. 4 is a detail top plan view of the pair of connected followers. Fig. 6 is a detail elevation of a modified form of the sweep-lever. Fig. 5 is a side elevation of a modified form of my improved press. Fig. 7 is a detail elevation of another modified form of the sweep-lever.

In the embodiment of my invention I provide a horizontal frame 1, which is rectangular in cross-section and comprises a pair of sills 2, a pair of plates 3, vertical studs 4, that connect the sills and plates, transverse bars 5, that connect the sills, and similar bars 6, that connect the plates. Standards 7 are also provided which connect the sills and plates together and are disposed midway between the ends of the frame. In opposite ends of the frame are formed press-boxes 8. The bottoms of the said press-boxes, which are indicated at 9, are supported on the cross-bars 5. The tops of the press-boxes are secured under the cross-bars 6, the said tops of the said boxes being indicated at 10. The sides 11 of the press-boxes are secured on the inner sides of the studs 4, and slots 12 are formed between the boards which constitute the sides for the tie-wires. The inner and outer ends of the press-boxes are open. Doors 13 are provided at the outer ends of the press-boxes to close the same. The inner ends of the press-boxes are at some distance apart, as shown in Figs. 1 and 2 of the drawings. I employ tie-bolts 14 to connect the sills and plates together and strengthen the construction of the press-boxes and their supporting frame.

In each of the press-boxes is a follower 15. The said followers are connected together by longitudinally-disposed bars 16, so that the 55 followers are adapted for simultaneous operation.

One of the standards 7 is provided with a bearing 17, in which is journaled an oscillating shaft 18, that is formed or provided with a crank-arm 19 at its inner end and a sweep-lever 20 at its outer end, which sweep-lever and crank-arm are preferably disposed in the same plane. The crank 21 of the crank-arm is connected by links 22 to the followers. As here 65 shown, the said links are provided with eyes or openings 23 at their inner ends to receive the crank 21 and are provided at their outer ends with openings 24, open on their lower sides to receive and engage pins 25, with 70 which the followers are provided. It will be understood from the foregoing that by moving the lever 20 the followers will be simultaneously operated in the press-boxes and that one of the followers will move outwardly 75 in one of the press-boxes while the other moves inwardly in the oppositely-disposed press-box.

Transversely-disposed shafts 26 are journaled in bearings at the ends of the plates 3. 80 Each of the said shafts is provided at one end with a drum 27 and a crank 28, by which it may be turned. Suitable ropes, cables, or chains 29 connect the sweep-lever 20 to the said drums, so that by turning one of the said 85 drums the said lever may be moved to impart the desired motion to the followers. It will be understood that owing to the length of the said lever 20 and the size of the drums 27 the power of the press is very great, and 90 the same is adapted for readily pressing hay, straw, or other material into bales.

It will be understood that while the follower is being moved outwardly in one of the press-boxes to form a bale therein the door 95 at the outer end of the opposite press-box may be opened to enable a previously-formed bale therein to be removed and material for another bale to be placed in the said press-box. Hence the operation of my improved 100 baling-press is practically continuous, a bale being formed in one of its boxes while the other box is being filled with material for another bale.

To reduce friction and facilitate the operation of my improved press, I provide the followers on their under sides with antifriction-rollers 30, which travel on the bottoms of the 5 press-boxes. To enable the length of the sweep-lever to be varied, so that the same may exert any desired leverage in operation, I propose to make the said sweep-lever of two sections *a b*, the one movable on the other, the 10 said sections being slidably connected together, either by the clips *c* here shown or by any other suitable means. This modified form of the sweep-lever is shown in Fig. 6 of the drawings.

15 In the modified form of my invention I substitute a sprocket-wheel 20^a of suitable size for the sweep-lever, sprocket-wheels 27^a for the winding-drums, and endless chains 29^a for the cords 29, the said chains connecting the 20 said sprocket-wheels 27^a to the said sprocket-wheel 20^a. It will be understood that the cranks 28 in both forms of my invention may be operated manually.

25 My improved baling-press is exceedingly cheap and simple, is strong, durable, and compact, may be readily assembled and disassembled, and is entirely efficient in operation.

In Fig. 7 of the drawings I show another modified form of the sweep-lever, in which 30 the same is composed of two sections *a b*, slidably connected together by clips *c*. The sections *a b* are preferably made of wood, and the inner section *a* is secured at its inner end to an arm *d*, that is made of iron or steel, is 35 preferably a casting, and is keyed to the outer end of its shaft 18. Said arm *d* has flanges *d'*, that bear on opposite sides of the section *a* to strengthen the connection between the latter and the said arm. This construction of the 40 sweep-lever enables the same to be com-

pactly disposed for transportation and facilitates the setting up of the press.

Having thus described my invention, I claim—

1. In a baling-press, the combination of a 45 pair of oppositely-disposed connected press-boxes, followers in the said press-boxes, a shaft journaled in a bearing disposed between said press-boxes, said shaft having a crank, connections between the latter and 50 said followers, to move said followers simultaneously, when said shaft is oscillated, an extensible lever secured to the said shaft, independently - revoluble power elements mounted on the said press-boxes and flexible 55 connections between said power elements and the outer portion of said extensible lever, substantially as described.

2. In a baling-press, the combination of a pair of oppositely-disposed connected press-boxes, followers in the said press-boxes, a shaft journaled in a bearing disposed between said press-boxes, said shaft having a crank, connections between the latter and 60 said followers, to move said followers simultaneously when said shaft is oscillated, an arm secured to said shaft, an extensible sweep-lever secured to said arm, independently-revoluble power elements mounted on the said 65 press-boxes and flexible connections between 70 said power elements and the outer portion of said extensible lever, substantially as described.

In testimony that I claim the foregoing as my own I have hereto affixed my signature in 75 the presence of two witnesses.

FRANCIS MARION CHAPPELL.
